UNITED STATES PATENT OFFICE.

GEORGE B. WOOD, OF DETROIT, MICHIGAN, ASSIGNOR OF ONE-HALF TO EDWARD L. WOOD, OF DETROIT, MICHIGAN.

DESIGN FOR A CAN OR SIMILAR RECEPTACLE.

Application filed October 18, 1926. Serial No. 19,404. Term of patent 14 years.

To all whom it may concern:

Be it known that I, GEORGE B. Wood, a citizen of the United States, residing at the city of Detroit, in the county of Wayne and State of Michigan, have invented a new, original, and ornamental Design for a Can or Similar Receptacle, of which the following is a specification, reference being had to the accompanying drawing, forming a part thereof.

The figure is a perspective view of a can or similar receptacle showing my new design.

I claim:

The ornamental design for a can or similar receptacle, as shown.

GEORGE B. WOOD.
